VEHICLE WHEEL

Hiroshi Ishibashi, Tokyo, Japan, assignor to Bridgestone
Cycle Industry Co., Ltd., Tokyo, Japan

Filed Oct. 10, 1972, Ser. No. 296,148

Claims priority, application Japan Apr. 10, 1972

Term of patent 7 years

Int. Cl. D12—16

U.S. Cl. D12—211

FIG. 1 is an enlarged front perspective view of a vehicle wheel showing my new design;

FIG. 2 is a front elevational view thereof;

FIG. 3 is a rear elevational view thereof;

FIG. 4 is a sectional view taken along the lines IV—IV of FIG. 2 in the direction indicated generally;

FIG. 5 is a sectional view taken along the lines V—V of FIG. 2 in the direction indicated generally; and

FIG. 6 is a side elevational view thereof.

I claim:

The ornamental design for a vehicle wheel, substantially as shown.
